UNITED STATES PATENT OFFICE.

RUFUS PORTER, OF WASHINGTON, DISTRICT OF COLUMBIA.

CHAIR-CANE.

Specification forming part of Letters Patent No. 11,271, dated July 11, 1854.

To all whom it may concern:

Be it known that I, RUFUS PORTER, of the city and county of Washington, and District of Columbia, have invented a new and useful Portable Chair, a walking cane or staff that may be instantly converted to a chair or table; and I do hereby declare that the following is a full and exact description thereof, reference being had to the annexed drawings, making part of this specification, in which—

Figure 1 is a perspective view of the chair in its expanded position. Fig. 2 is a vertical section of the same. Fig. 3 is a vertical section of the invention in the compact form of a cane, and Fig. 4 is an elevation of the same.

To a vertical shaft B one foot long and five-eighths of an inch in diameter is attached a cylindrical hub C two inches long and one and a quarter inch in diameter. The upper portion of the shaft, which extends five inches above the hub, is round, but the portion below the hub is square. In the lower end of the hub are four slots corresponding to the four faces of the shaft, and into each of these slots is fitted a tenon e, which is formed upon the upper end of a vertical leg D and secured in the slot by a horizontal pivot n, which extends through the tenon and a portion of the hub from c to c. Each of the four legs is one foot long and of a segmental form, but with its edges mitered, so that the four, when in contact with the shaft, assume a cylindrical form.

Upon the square portion of the shaft is mounted a sliding socket E, to which are connected by hinge-joints the upper ends of four radial wire braces F, the lower ends of which are connected by staples to the four legs near the bottom thereof, and the socket E is prevented from passing off from the bottom of the shaft by the pin r.

Another hub G, of equal dimensions with the hub C, is mounted upon the round part of the shaft B and has four slots in the upper end thereof, into which are fitted four tenons o, which are formed upon the lower ends of four arms H and secured in the slots by pivots u, and to the heads of these arms are attached the four corners of a square piece of canvas W, which constitutes the seat of a chair or top of a table.

Upon the shaft B, above the hub G, is

mounted a sliding socket I, in the top of which are four slots which receive the centerward ends of four radial wire braces J, through which pass four pivots or an iron ring, which is inclosed in the metal of the socket. The outward ends of these braces are connected by staples to the four arms near the upper ends thereof.

The shaft B is surmounted by a cap T, which prevents the socket I from sliding off therefrom, and when the said socket is elevated to the cap the arms H are held at an angle of about fifty degrees with the shaft B, and the socket I is prevented from descending by means of two opposite spring-checks s. The arms are of a segmental form with mitered edges and assume a cylindrical form when brought up to a compact position, and when required to remain in that position the portions of the canvas which protrude between the arms are wrapped around the arms and the arms and canvas are secured by a tube or sheath M, to the top of which is attached a head A.

The legs when in the compact position assume a cylindrical form and are secured in that position by a ferrule or band m, the bottom of which is attached to a foot-post Z, which is about fourteen inches long and of diameter corresponding to that of the compact form of the legs. Five inches of the upper part of the foot-post is reduced to the form of a square tenon K, which is inserted in the square cavity between the four legs, and the band m binds the exterior. The legs and foot-post are slightly conical, tapering from the hubs to the bottom.

A metallic plate-ring X, half an inch wide and having its upper edge bent inward, is attached to the top of the hub C, but the upper edge extends an eighth of an inch above the hub C and the bent edge or flange enters a groove v, which is cut in the hub G.

When this device is to be used as a table, the several parts are made of larger dimensions, and a single hub with slots in each end may answer the purpose of two. The center shaft may in that case extend as high as the arms. Both arms and legs have small grooves cut longitudinally on the inside thereof to accommodate the wire braces when in the compact position.

What I claim as my invention, and desire to secure by Letters Patent, is—

Constructing a chair or table by hinging four arms and four legs to a hub or hubs attached to or mounted upon a central vertical shaft and supporting said arms and legs by radial braces which connect said arms and

legs to sliding sockets in such a manner that the said arms and legs may be closed up to a compact form, as herein described.

RUFUS PORTER.
